UNITED STATES PATENT OFFICE

90,532

DESIGN FOR A CORNICE CURTAIN POLE

Charles W. Kirsch, Sturgis, Mich.

Application January 2, 1932. Serial No. 42,346

Term of patent 7 years

To all whom it may concern:

Be it known that I, CHARLES W. KIRSCH, a citizen of the United States and a resident of Sturgis, in the county of St. Joseph and State of Michigan, have invented a new, original, and ornamental Design for a Cornice Curtain Pole, of which the following is a specification, reference being had to the accompanying drawing,

forming a part thereof wherein Fig. 1 is a perspective view of a cornice curtain pole embodying the design, and Fig. 2 is a front elevation of the same.

I claim:

The ornamental design for a cornice curtain pole as shown.

CHARLES W. KIRSCH.
